DISPLAY CABINET

Edwin A. Shank, New Rochelle, N. Y.

Application March 3, 1939, Serial No. 259,543

1 Claim. (Cl. 211—184)

My invention relates to display cabinets and particularly relates to multi-compartment display cabinets of the folding or "knock-down" type; that is, cabinets which may be folded and collapsed when not in use so that their bulk is materially reduced for storage and transportation purposes.

The main object of my invention is the provision of a display cabinet comprising a plurality of wall members hingedly secured to a rear wall member so that when opened they define, with the wall member, a multi-compartment display cabinet, and when closed, will lie flatly against one another.

15 A further object of my invention is to provide a device of the character described which has a number of intermediate wall portions dividing the cabinet into a plurality of compartments.

20 A further object of my invention is the provision of a device of the character described which is simple and easy to manufacture and assemble and of relatively low cost.

Referring to the drawing annexed hereto and 25 forming a part hereof.

Figure 1 is a perspective view of one form of device constructed according to and embodying my invention;

Fig. 2 is a perspective view of the device of 30 my invention in folded or collapsed form;

Fig. 3 is an end elevational view of one end wall member;

Fig. 4 is a horizontal section on the line 4—4 of Fig. 3; and

35 Fig. 5 is a vertical section on the line 5—5 of Fig. 1.

Reference numeral 10 indicates my new and improved cabinet generally, which comprises a rear wall 12, a front wall 14 and a plurality of 40 compartment wall members 16 pivotally connected to the wall members 12 and 14. In the herein-described and illustrated embodiment of my invention, three compartment wall members 16 are shown, dividing the cabinet into two 45 compartments, A and B, but this is for illustration only and my invention is not to be limited to a double-compartment cabinet. My invention will operate equally well with any reasonable number of compartments.

50 The rear or base wall 12 comprises a sheet of light gage metal of generally rectangular shape. The compartment wall members 16 are similarly formed of light gage metal, and may be of any desired size or shape, limited only in that the 55 lower horizontal edge 18 is straight and the rear

vertical edge 20 is similarly straight, for reasons to be pointed out below.

In the preferred form of my invention, compartment walls 16 are all of identical size and shape. Along the bottom horizontal edge 18 of each compartment wall 16, portions are cut or stamped out therefrom as at the front 21 and the rear 23. Portions are also cut or stamped out therefrom along rear vertical edge 20, spaced in from the extremities thereof, as at 10 25, 25. The peripheral edges of each wall member are bent or rolled into hollow tubes and a suitable wire threaded into the tubes, which wires serve not only to stiffen the wall members and impart rigidity thereto, but also to secure the 15 wall members to the base member 12.

I provide a plurality of tubular members 26, 26 which are formed of small narrow strips of suitable light-gage metal, doubled over to form open-ended tubes. These tubes 26, 26 are arranged in pairs and disposed and secured in vertical alignment on rear wall 12, as by spot welding or threading through suitably formed slits in said rear wall (not shown). These loops are of such size and are so spaced as to be received within openings 25, 25 in the rear vertical edge 20 of each of the compartment wall members.

The tube formed along the horizontal lower edge 18 of each compartment wall member 16 30 is indicated by reference numeral 30, and the tube formed along the vertical rear edge 20 of each wall member is indicated by reference numeral 32. A single wire 34 is threaded through these tubes and through the rear wall tubes 26, 26 aligned therewith. The wire 34 is of such length that the front end 36 thereof projects outwardly from the wall into the cut-out portion 21, and is bent up, at right angles, as at 38. The remaining edge 40 of each wall 16 is similarly 40 formed into a tube 42, and a wire 44 threaded thereto. The lower-edge 46 of wire 44 is extended downwardly into the cut-out portion 21 in line with the upstanding end 38 of wire 34.

Front wall member 14, also a stamping, is 45 of such height as to fit within the cut-out portions 21 of each wall member, and is of width equal to the width of rear wall 12. The longitudinal edges of front wall member 12 are bent or rolled over as at 50, 50, and a plurality of 50 vertically aligned openings 52, 52 are formed in the bent over portions 50, 50 into which openings are passed the extensions 46 of wires 44 and the aligned extensions 38 of wires 34, completing the assembly of my cabinet and secur- 55

ing the parts in position. The number of pairs of openings 52 correspond to the number of compartment wall members. The vertical edges 55 of wall 14 are also bent or rolled over to form tubes into which the two wire components of the endmost wall members may be passed.

To open the device for use, the wall members 16 are pivoted out at right angles to the base wall 12 defining the two compartments A and B, 10 and the device as a whole disposed to rest on its horizontal lower edges 18, 18. When not in use, or when arranged for shipment or storage, the device is collapsed and the parts arranged so that the compartment wall members 16, 16 15 are disposed flatly against each other, sandwiched in between the front and rear walls 14, 12, resulting in a neat, compact, easily handled unit.

I claim:

A knock-down display cabinet comprising a rear wall portion, a plurality of compartment wall portions each having a straight horizontal lower edge and a straight vertical rear edge 5 and having cut-outs at the front thereof adjacent the lower edge, a front wall portion of size to fit within the cut-outs, means to pivotally secure said compartment walls to the front and rear walls, the marginal edges of all the compartment wall members being provided with tubular members having wires threaded therethrough, the ends of which wires project at the cut-outs, and the front wall portion has means thereon to receive the projecting ends of the 15 wires for pivotal engagement with said compartment wall portions.

EDWIN A. SHANK.
